Primary Examiner—Doris Clark(74) *Attorney, Agent, or Firm*—Waddey & Patterson; David B. Pieper(57) **CLAIM**

What is claimed is the ornamental design for a fence cap insulator, as shown and described.

DESCRIPTION

FIG. 1 is a top-front isometric view showing the fence cap insulator of Applicant's invention.

FIG. 2 is a bottom-front isometric view showing the fence cap insulator of Applicant's invention.

FIG. 3 is a back elevation the fence cap insulator of Applicant's invention.

FIG. 4 is a right side elevation of the fence cap insulator of Applicant's invention.

FIG. 5 is a top elevation of the fence cap insulator of Applicant's invention.

FIG. 6 is a left side elevation of the fence cap insulator of Applicant's invention.

FIG. 7 is a front elevation of the fence cap insulator of Applicant's invention, and,

FIG. 8 is a bottom view of the fence cap insulator of Applicant's invention.
